UNITED STATES PATENT OFFICE.

ROBERT W. MILLER, OF WOODLAWN, PENNSYLVANIA.

OIL-CLOTH-VENDING APPARATUS.

1,214,209.

Specification of Letters Patent. Patented Jan. 30, 1917.

Application filed October 23, 1915. Serial No. 57,568.

To all whom it may concern:

Be it known that I, ROBERT W. MILLER, residing at Woodlawn, in the county of Beaver and State of Pennsylvania, a citizen 5 of the United States, have invented or discovered certain new and useful Improvements in Oil-Cloth-Vending Apparatus, of which improvement the following is a specification.

10 My invention relates to apparatus for vending oil cloth, and the object thereof is to provide a simple and practical apparatus for this purpose whereby such cloth may be easily and accurately measured and effectively cut into desired lengths.

15 In the accompanying sheets of drawings, which form part of my specification, and in which I have illustrated the preferred embodiment of my invention, Figure 1 is a 20 plan view of the apparatus; Figs. 2 and 3 are, respectively, front and side elevations thereof; Fig. 4 a vertical sectional view taken on the line IV—IV, Fig. 2; Fig. 5 a detail sectional view to enlarged scale, taken 25 on the line V—V, Fig. 2; and Fig. 6 a sectional view taken on the line VI—VI, Fig. 5.

In the several figures like numerals are used to designate like parts.

30 In my improved apparatus I provide a frame which may be of any suitable construction, that shown herein consisting of oppositely disposed pairs of legs 1 and 1^a, sustaining, at their upper ends supporting beams 2 and 2^a, and suitably braced by 35 cross bars 3. Upon the beams 2 and 2^a there is rotatably mounted a stock reel 4, which may be arranged to hold any desired number of rolls of oil cloth. As shown herein, provision is made for six of such rolls, and 40 to hold the reel from rotating while cloth is being drawn from one roll the reel is provided with a plurality of eyes 16 adapted to be engaged by a hook 17 secured to the beam 2^a. Adjacent to the reel 4, and 45 secured to the protruding ends of the beams 2 and 2^a, I provide a cutting board 5. To hold the cloth firmly upon such board while it is being cut, a hold-down bar 6 is hinged or otherwise secured for pivotal movement 50 to one end of the cutting board 5. The other end of the bar 6 is provided with means for moving it and clamping it firmly against the face of the cutting board. For this purpose I preferably provide an arm 7 55 pivoted to the beam 2^a and connected to the otherwise free end of the cutting bar 6 by

means of a link 8. The cutting bar, as shown particularly in Figs. 5 and 6, is grooved to receive and retain for longitudinal movement a cutter support or carriage 60 9, provided with a rotatable cutting disk 10. As will be readily understood, the construction and arrangement of the cutting board and hold-down bar is such that a desired length of oil cloth may, when the 65 bar 6 is in the position indicated by dotted lines in Fig. 2, be drawn from a stock roll and between such board and bar. The arm 7 may then be turned downwardly to the full line position, thus clamping the cloth 70 firmly to the board. Finally, the cloth may be cut by sliding the cutter carriage longitudinally of the bar 6.

To receive and measure the cloth I provide a reel 11 pivotally mounted in suitable 75 arms 12 and 12^a secured to the frame. As shown particularly in Figs. 3 and 4, the reel 11 is provided with spring clamps 13 to engage the end of the oil cloth. Furthermore, at one side of the reel and in line 80 with the clamps 13, there is attached the end of a measuring tape 14, which extends over the cutting board 5 and is secured at its other end to a suitable take-up device 85 15 attached to the beam 2^a. Thus to measure a certain length of cloth it is only necessary to place the end of the cloth in the clamps 13 of the reel 11, and turn such reel until the measuring tape at the front edge of the bar 6 reads the required length, it 90 being understood that the turning of the reel simultaneously and in equal lengths, withdraws the cloth from the stock reel 4 and the tape from the take-up device 15. When the cloth is cut, it may be removed 95 from the reel 11, the tape 14 being simultaneously taken up by the take-up device 15.

I claim as my invention:

In an oil cloth vending apparatus, the 100 combination of a frame, a stock reel and a receiving and measuring reel rotatably mounted thereon, a cutting board secured to the frame between said reels, a clamp borne by the receiving reel for engaging 105 oil cloth, a measuring tape and take-up device therefor secured to said frame adjacent to one end of the receiving reel, said tape extending over the cutting board and having its outer end secured to said receiving 110 reel at a point in line with said clamp, a hold-down bar pivoted at one side of and

adapted to hold the cloth firmly against said cutting board, means secured to the other end of said bar for clamping it against said cutting board and upon a sheet of oil cloth to hold it firmly upon said board, and a cutter slidably mounted upon said bar.

In testimony whereof I have hereunto set my hand.

ROBERT W. MILLER.
